TEMPLATE FOR LOCK PLATE MORTISES

Elmer P. Sacrey, Liverpool, N. Y.

Application May 20, 1930, Serial No. 454,098

13 Claims. (Cl. 33—197)

This invention has for its object to provide a simple, efficient and readily operated template for locating the mortise in the edge of an element, as a door, to be provided with a mortise for receiving a lock plate, it being understood that door locks are set in recesses or mortises in the edge of the door so that the plate is flush with the edge surface of the door.

The invention consists in the novel features and in the combinations and constructions hereinafter set forth and claimed.

In describing this invention, reference is had to the accompanying drawing in which like characters designate corresponding parts in all the views.

Figure 1 is an elevation of this template.

Figure 2 is an end view looking downwardly or upwardly showing the same applied to an element, as a door, which is shown in section.

Figure 3 is a sectional view on line 3—3, Figure 1.

Figure 4 is a fragmentary sectional view on line 4—4, Figure 1.

Although this template is particularly adapted for locating the mortises for lock plates, it will be understood that it is equally as useful in locating the mortises and recesses in the edges of any other element.

This template comprises generally a body, mortise locating gages carried by the body and adjustable to determine the length and width of the mortise and means for supporting the body on the edge of the door or other element with the gages overlying the edge of the door and for centering the gages so that the mortise will be located in the center or any other predetermined position in the edge of the door, during the operation or the supporting or clamping means.

1 designates the body which may be of any suitable form, size and construction, it being here shown as a plate rectangular in form with angular marginal flanges 2 so that the body is in the form of a hollow pan. It is also provided with a lengthwise slot 3 in the bottom of the pan.

45 The gages include side gages 4, 5 and end gages 6, 7. The side gages 4, 5 are adjustable toward and from each other to determine the width of the mortise and one of the end gages is adjustable toward the other which is fixed for determining the length of the mortise. The side gages are connected through one of the end gages so that the adjusting movement of either side gage is transmitted to the other.

In the illustrated embodiment of my invention, 55 each side gage is supported by a pair of links

8, 9 pivoted at like ends at 10 to one of the side gages and at their other ends at 11 to the body, the links and the gages being arranged so that the gages always move parallel to themselves and to each other. Obviously, movement of the links in one direction will move the corresponding gages 4, 5 outwardly away from each other and movement in the other direction will move them inwardly toward each other. One of the end gages as 6 is fixed in any suitable manner as by rivets 2 to one of the side gages as the gage 4 and is connected to the other side gage as 5 by an adjustable or pin-and-slot connection consisting of a slot 13 in the gage 6 and a threaded pin or screw 14 extending through the slot and threading into the gage 5, the screw having a finger piece 15 at its outer end.

7 designates an adjustable end gage which is here shown as adjustably secured to one of the side gages, as the side gage 4 and as slidable along the other side gage 5. The end gage 7 is here shown as held in its adjusted position by a clamping screw 17 extending through the gage 7 and threading into a block or jaw 18 which clamps the underside of the side gage 4, the jaw 18 being provided with a tenon which interlocks in a groove in the underside of the gage 4. By loosening the screw 17, obviously, the end gage 7 can be slid along the side gage 4 to any desired position. Obviously, by loosening the screw 14 and moving either one or the other of the side gages 4 or 5, the movement thereof will be transmitted through the connection 6 to the other gage and then when the screw 14 is tightened, the side gages will be held in their adjusted spaced apart position, thus determining the width of the mortise and then by loosening the screw 17, the end gage 7 can be moved toward or from the end gage 6, thus determining the length of the mortise.

The means for supporting the body on the edge of the door or other element, as here illustrated, comprises a pair of movable parts, as jaws, located at each end of the body, and means for operating the jaws and holding the body centered relatively to the edge of the door or for operating the jaws, permitting the body to remain stationary.

20 and 21 designate the jaws of each pair, there being a pair at each end of the body, these jaws being arranged to clamp the outer and inner sides of the door. The operating member is shown as a screw common to the jaws of each pair, the screw having right and left screw threaded connection with the jaws 20, 21 respectively. The

105 110 115

screw is held from endwise movement relatively to the body so that when the screw is turned, the jaws will move toward or from each other, and hence the body and side gages are held centered 5 relatively to the edge of the door.

22 designates the screw or operating member having a handle 23 at one end. The means for holding the screw from endwise movement is here shown as a collar 24 fixed on the screw and coacting 10 with thrust bearings connected to the body. As here shown, the collar is located in a slot formed in a block 25 which is secured to the end of the body, there being a block 25 at each end of the body. Each of the jaws 20, 21 is provided 15 with means for slidably interlocking with the block or extensions 26 thereof to hold the jaws from turning during the turning movement of the screw 22. In order that the body may conform to the bevel of the edge of the door, the body is connected to the blocks 25 by swivel joints 27.

In operation, the location of either the upper or lower end of the mortise may be located by drawing a line on the edge of the door. We will assume that this line indicates the upper end of the mortise. The length and width of the mortise is determined by the length and width of the lock plate or other member to be set in the mortise. This factor having been determined, the operator 30 loosens the screw 14 and adjusts the gages 4, 5 so that they are separated a distance equal to the width of the lock plate plus sufficient minimum clearance for the tool used to cut the recess. He then tightens the screw 14 maintaining 35 or locking the side gages 4, 5 in their adjusted position. He then adjusts the end gage 7 toward or from the gage 6 and in accordance with the length of the lock plate plus sufficient minimum clearance for the tool. The clearances are about 40 one-sixteenth of an inch. He then places the template on the edge of the door with the edge of the end gage 6 in line with the line before referred to, which has been previously placed on the door. If the edge of the door is bevelled, the 45 body is turned so that the plate lies flatwise on the edge of the door, the swivel joints 27 permitting this turning.

The bevel is so slight that the turning of the body about the swivel joints does not upset, to 50 any practical extent, the centering of the mortise or does not materially displace the gages, or in other words, because the bevel is so slight, the gages can be set to locate the mortise in the center of the edge of the door as if the edge of the 55 door were not bevelled and the location of the mortise will not be upset by the slight bevel. During the tightening of the operating members 22, the jaws 20, 21 are drawn toward each other clamping on opposite sides of the door without 60 shifting the body to the right or left or upsetting the central location of the mortise or the gages which determine the position of the mortise. After the template has been applied, and hence the 65 mortise located, the mortise can easily be routed out by suitable tools, as for instance, a router, set to a certain depth and guided by the pan with the angular flanges 2.

This template is particularly advantageous in 70 that it is readily applied to the door or other element and accurately adjusted to the size of the mortise to be cut and accurately located or centered on the door or other element.

What I claim is:

1. A template for mortises comprising a body, 75 mortise locating gages carried by the body and

means for supporting the body on an element to be provided with a mortise with the gages overlying an edge of said element, the body being swivelled to the supporting means for permitting the body and the gages carried thereby to be 80 shifted relatively to the supporting means to conform to a bevel of the edge of said element.

2. A template for mortises comprising a body, 85 mortise locating gages carried by the body and means for supporting the body on an element to be provided with a mortise with the gages overlying an edge of said element, said means comprising a block at each end of the body, a pair of movable parts slidably engaged with the block and coacting with said element to secure the body to said element, and an operating member carried by the block for operating said parts, the body being swivelled at its ends to the blocks.

3. A template for mortises comprising a body, 90 mortise locating gages carried by the body, and means for supporting the body on an element to be provided with a mortise with the gages overlying an edge of said element, said means comprising a block at one end of the body, a pair of jaws for engaging the opposite faces of said 100 element, the jaws having means slidably engaging the block, an operating member having a right and left screw threaded connection with the jaws respectively and means for holding the operating member from endwise movement, the 105 body being swivelled to the block.

4. A template for mortises comprising a body, 110 mortise locating gages carried by the body comprising side gages adjustable toward and from each other for determining the width of the mortise and connections between the side gages whereby movement of one gage effects the corresponding movement of the other gage and means for supporting the body on an element to be provided with a mortise with the gages overlying 115 an edge of said element, said connections being located outside of the area of the gaged opening, so as not to interfere with the routing tool.

5. A template for mortises comprising a body, 120 mortise locating gages carried by the body comprising opposing side gages, connections between the gages and the body permitting movement of the gages to determine the width of the mortise and connections between the gages whereby movement of one gage toward the other effects 125 a corresponding movement of the other toward the first and vice versa and means for supporting the body on an element to be provided with a mortise with the gages overlying an edge of said element, all of said connections being located 130 outside of the area of the gaged opening, so as not to interfere with the routing tool.

6. A template for mortises comprising a body, 135 mortise locating gages carried by the body comprising a pair of side gages, links pivoted at like ends respectively to each gage and at their other ends to the body, the links and the gages being arranged so that the gages always move parallel to themselves and to each other, a connection between the gages whereby the movement of one 140 gage is transferred to the other and means for supporting the body on an element to be provided with a mortise with the gages overlying an edge of said element.

7. A template for mortises comprising a body, 145 mortise locating gages carried by the body comprising opposing sides gages adjustable toward and from each other, and end gages, one of which is carried by one of the side gages and adjustable along the same and the other of which is fixed to 150

one of the side gages and adjustably connected to the other side gage and serving to transmit the movement of one side gage to the other.

8. A template for mortises comprising a body, 5 mortise locating gages carried by the body comprising a pair of side gages, connections between the side gages and the body permitting shifting movement of the gages toward and from each other to determine the width of the mortise, an 10 end gage connecting like ends of the side gages and being fixed to one side gage, a pin and slot connection between the end gage and the other side gage, an adjustable end gage carried by one of the side gages and adjustable toward and from the other end gage to determine the length 15 of the mortise, said pin and slot connection being capable of being tightened when the side gages are in their adjusted position and means for supporting the body on an element to be provided with a mortise with the gages overlying an edge of said element.
9. A template for mortises comprising a body, 20 mortise locating gages carried by the body and comprising side gages and end gages, links pivoted at like ends to each of the side gages at their other ends to the body, the links and the side gages being arranged so that the gages always move parallel to themselves and to each other, whereby movement of the links moves the side 25 gages toward and from the other to determine the width of the mortise, an end gage fixed to one of the side gages, a pin and slot connection between the end gage and the other side gage and serving to transmit the motion of one side gage to the other, said pin and slot connection being capable of being tightened when the side gages are in their adjusted position and a second 30 end gage adjustably mounted on one of the side gages and movable toward and from the other end gage to determine the length of the mortise and means for supporting the body on an element to be provided with a mortise with the gages overlying an edge of said element.
10. A template for mortises comprising an 35 elongated body, mortise locating gages carried by the body and means for supporting the body on an element to be provided with a mortise with the gages overlying an edge of said element, the body being movable relative to the supporting means about an axis extending lengthwise of the body for permitting the body and the gages carried 40 thereby to be moved relatively to the supporting means to conform with the bevel of an edge of said element.
11. A template for mortises comprising a body, 45 mortise locating gages carried by the body and including opposing side gages adjustable toward and from each other, and end gages, one of which is fixed to one of the side gages and adjustably connected to the other side gage to transmit the movement of one side gage to the other, the other end gage being adjustable relative to the first end gage.
12. A template for mortises comprising a body, 50 mortise locating gages carried by the body and including a pair of said gages, connections between the side gages and the body permitting shifting movement of the gages toward and from each other to determine the width of the mortise, an end gage connecting like ends of the side gages and being fixed to one side gage, a pin and slot connection between the end gage and the other side gage, a second end gage adjustable toward and from the other end gage to determine the length of the mortise, said pin and slot connection being capable of being tightened when the side gages are in their adjusted position and means for supporting the body on an element to be provided with a mortise with the gages overlying an edge of said element.
13. A template for mortises comprising a body, 55 mortise locating gages carried by the body and including side gages and end gages, links pivoted at like ends to each of the side gages at their other ends to the body, the links and the side gages being arranged so that the gages always move parallel to themselves and to each other, whereby movement of the links moves the side gages toward and from the other to determine the width of the mortise, an end gage fixed to one of the side gages, a pin and slot connection between the end gage and the other side gage and serving to transmit the motion of one side gage to the other, said pin and slot connection being capable of being tightened when the side gages are in their adjusted position and a second end gage 60 adjustable toward and from the other end gage to determine the length of the mortise and means for supporting the body on an element to be provided with a mortise with the gages overlying an edge of said element.
